UNITED STATES PATENT OFFICE.

WILLIAM A. WALKER, OF RACINE, WISCONSIN, ASSIGNOR TO OTTO R. BARNETT, OF CHICAGO, ILLINOIS.

RAIL-ANCHOR.

1,134,567.

Specification of Letters Patent.

Patented Apr. 6, 1915.

Application filed July 19, 1913. Serial No. 780,021.

To all whom it may concern:

Be it known that I, WILLIAM A. WALKER, a citizen of the United States, residing at Racine, in the county of Racine and State of Wisconsin, have invented certain new and useful Improvements in Rail-Anchors, of which the following is a specification.

My invention relates to devices for preventing the longitudinal creep of railroad rails, these devices being variously called rail anchors, anti-creepers, or rail stays; and the object of the invention is to provide an expedient for preventing the clamp of the device on the rail from being disturbed or loosened by the vibration of the rails under the stresses of the car wheels, by the expansion and contraction of metal with temperature changes, or from other causes, which will be positive in its action and will add but little to the cost of producing the rail anchors to which it is applied. This expedient is of particular value and utility in rail anchors, consisting of one or more parts, which depend for the security of their grip 25 on the rail upon being driven or forced into engagement with the rail in a direction toward the tie against which the anchor abuts.

The invention is illustrated and will be described in connection with two species of anchor of this general type, one of these being a one-piece anchor and the other a two-piece anchor. It will be apparent, however, that the same expedient might be used with effect and advantage in rail anchors different in construction from those shown.

Referring to the drawings, Figure 1 is a plan view of a one-piece rail anchor shown as applied to the rail and provided with the device of my invention; Fig. 2, a sectional view taken on line 2—2 of Fig. 1; Fig. 3, a plan view of a two-piece anchor utilizing substantially the same expedient, and Fig. 4, a sectional elevation of the same.

Like characters of reference designate like parts in the several figures of the drawings.

Referring first to Figs. 1 and 2, the anchor herein shown consists of an integral metal strap A which extends around the base of the rail B and is provided with a tie abutting member C which bears against one of the ties D on which the rail is supported. It will be obvious that the part C might abut against any stationary part or element of the roadbed and I do not wish to have the term "tie abutting member" used in de-

scribing this part of the device considered as excluding such arrangement. The strap A is provided at opposite ends with jaws E and F which engage opposite edges of the rail base. The device is put into operative position by driving the end having the jaw F thereon toward the tie D, the strap taking the oblique position shown in Fig. 1. It will be understood that on a double track road a rail anchor of this sort is placed on the side of the tie toward which the travel moves, the travel of the trains being indicated by the feathered arrow in Fig. 1. The stress produced by the wheels, therefore, tends to tighten the grip of the anchor on the rail at the time the rail has to be held against its tendency to creep. However, in devices of this character there is always danger that the device will be shaken or loosened from its operative engagement with the rail either by vibration, expansion and contraction of metal due to temperature changes or the reactionary stress which is thought to be set up in a rail after the train has passed over it. My invention provides for positively preventing the loosening of the grip of the device on the rail due to these or any other similar causes, by providing one or other of the jaws, preferably jaw F, with a set screw G which preferably passes through a threaded perforation in the jaw and can be driven in so as to tightly engage the base flange of the rail after the anchor has been adjusted or forced to its operative position without danger of loosening the jaw's grip on the base flange. Preferably the end of the set screw is concave as shown at g so as to bite into and take a better grip on the base of the rail.

In Figs. 3 and 4 I have shown substantially the same expedient applied to a two-piece rail anchor. The device, in this case, consists of a jaw casting H provided with a tie abutting member J and a strap K formed at one end with a jaw L which engages one edge of the rail base, and at the other, with a jaw M which extends around the jaw casting H, being preferably held in place between abutments N, O on said casting. The strap K takes an oblique position when it operatively engages the rail. To prevent it from backing away from the tie and thereby destroying the hold of the rail stay on the rail my invention provides the jaw L with a set screw P which preferably is ar-

ranged so as to bite into the upper surface of the base flange of the rail.

I have shown the expedient constituting my present invention as applied to two types of rail anchor but it will be obvious that it might be employed in connection with other types comprising one or more elements which must be held against retrograde movement in order that the anchor should be efficient in its operation.

I claim:

1. In a rail anchor comprising a jaw, the combination with a tie abutting member, of rail gripping means comprising a jaw engaging one of the base flanges of the rail, and a set screw in said jaw which is adapted to be driven into engagement with said base flange.
2. In a rail anchor, the combination with rail gripping means comprising a jaw in engagement with the upper surface of the base flange of the rail, of a set screw in said jaw which is adapted to be driven into engagement with said base flange.
3. In a rail anchor, the combination with a strap extending around the base of the rail

which is adjusted to its operative position by having one end forced toward the tie against which said anchor abuts, of a set screw in the end of said strap adapted to be driven against said rail, for the purpose described.

4. In a rail anchor the combination with a strap extending around the base of the rail which is adjusted to its operative position by having one end forced toward the tie against which said anchor abuts, of a set screw which extends through said end of said strap and engages the edge of the rail base.

5. A rail anchor comprising an integral casting formed on one end with a tie abutting member and on each end with a jaw to engage opposite edges of the base of a rail, and a set screw extending through one of said jaws adapted to engage the base of said rail, for the purpose described.

WILLIAM A. WALKER.
